(57) **CLAIM**

The ornamental design for a front end loader of tractor, as shown and described.

DESCRIPTION

FIG. 1 is a perspective view of a front end loader of tractor showing the claimed design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is another perspective view of the front end loader of tractor attached to the tractor.

The broken lines are for illustrative purposes only and form no part of the claimed design.

1 Claim, 8 Drawing Sheets
